CLAIM

The ornamental design for a pair of light bar brackets, as shown and described.

DESCRIPTION

FIG. 1 is a front perspective view of the pair of light bar brackets shown in use condition showing my new design; FIG. 2 is a front side elevation view thereof; FIG. 3 is a rear side elevation view thereof; FIG. 4 is a left side elevation view thereof; FIG. 5 is a right side elevation view thereof; FIG. 6 is a top plan view thereof; and, FIG. 7 is a bottom plan view thereof.

The dot-dot-dash broken lines shown in the vehicle body depicted in FIG. 1 illustrate vehicle environmental subject matter which forms no part of the claimed design. The evenly spaced broken lines in the drawings illustrate portions of the pair of light bar brackets and form no part of the claimed design.
